[57] **CLAIM**

The ornamental design for a magnetic disc storage case, as substantially shown and described.

DESCRIPTION

FIG. 1 is a perspective view of a magnetic disc storage case showing my new design;

FIG. 2 is a top plan view thereof;

FIG. 3 is a right side elevational view;

FIG. 4 is a cross sectional view taken along line 4—4 of FIG. 2;

FIG. 5 is a front elevational view of FIG. 1;

FIG. 6 is a bottom plan view thereof; and,

FIG. 7 is a right side elevational view with the pivoted tray placed in a vertical position.
